Primary Examiner — Karen S Acker(74) *Attorney, Agent, or Firm* — Wood, Herron & Evans, LLP(57) **CLAIM**

The ornamental design for a sheet material with camouflage pattern, as shown and described.

DESCRIPTION

The file of this patent contains at least one drawing executed in color. Copies of this patent with color drawings will be provided by the U.S. Patent and Trademark Office upon request and payment of the necessary fee.

FIG. 1 is a top plan view of a first embodiment of a sheet material with camouflage pattern according to my new design; and,

FIG. 2 is a top plan view of a second embodiment thereof. The broken lines surrounding the sheet material with camouflage pattern represent the boundaries of the claim and form no part thereof.
